INVENTOR

BY Victor J. Evans & Co.

ATTORNEY

UNITED STATES PATENT OFFICE

2,046,221

COUPLING

William O. Thomas, Anderson, Ind.

Application July 28, 1933, Serial No. 682,678
Renewed May 21, 1936

2 Claims. (Cl. 200—115.5)

This invention relates to couplings and its general object is to provide a coupling for connecting together electrical conductors and other devices to which my coupling is applicable, in an easy, expeditious and secure manner, and against both endwise and circumferential displacement relative to each other.

A further object of the invention is to provide a coupling of the character set forth, that is simple in construction, inexpensive to manufacture and extremely efficient in use and service.

This invention also consists in certain other features of construction and in the combination and arrangement of the several parts, to be hereinafter fully described, illustrated in the accompanying drawing and specifically pointed out in the appended claims.

In describing my invention in detail, reference will be had to the accompanying drawing wherefore like characters denote like or corresponding parts throughout the several views, and in which:

Figure 1 is a plan view illustrating my invention in a form to interconnect opposed terminals of electrical conductors.

Figure 2 is a sectional view taken approximately on line 2—2 of Figure 1.

Figure 3 is a sectional view taken approximately on line 3—3 of Figure 2.

Figure 4 is a perspective view of the companion members of the electrical coupling separated.

Figure 5 is a sectional view of a modified form of the electrical coupling or connector.

Figure 6 is a sectional view taken approximately on line 6—6 of Figure 5.

Referring to the drawing in detail, and particularly to Figures 1 to 4 inclusive I provide a pair of companion members 11 and 12 that are formed from insulating material and each of the members 11 and 12 are provided with passageways through which pass the conductors as shown. The conductors have formed on their adjacent ends, enlarged terminals 13 providing heads which are received in contact with the ends 45 of bores arranged centrally and longitudinally of the respective members 11 and 12, and these bores cooperate with each other to provide a chamber for a fuse 14, the chamber being indicated by the reference numeral 15. It will be noted that the ends of the bores which provide the chamber 15 are substantially conical shape and the heads are shaped accordingly to fit the same. By that construction, it will be obvious that the conductors are held associated with the coupling and 55 withdrawal thereof is impossible. The fuse is of

the refillable link type and is provided with conical shaped ends to be received and fit in like shaped recesses formed in the heads or terminals 13, as clearly shown in Figure 2.

The member 12 is provided with bayonet slots 5 16 and 17 which have mouth portions 18 and 19 and the bayonet slots are adapted to receive lugs 21 and 22 when the members 11 and 12 are associated as will be apparent upon inspection of Figure 4.

The circumferential portions of the bayonet slots 16 and 17 are inclined toward the outer end of the member 12 in a substantially spiral manner, and the member 12 has arranged in a strip portion disposed inwardly of the groove 16 15 a longitudinally disposed slot 23 for the purpose of receiving the head 24 of a pawl 25 which is pivoted as at 26 in a groove 27 arranged longitudinally in the member 11. The pawl in this form of the invention is likewise spring pressed 20 through the instrumentality of a coil spring 28 so as to urge the head 24 in the groove 23 when the members are associated, as clearly shown in Figure 2.

A passage 29 is provided in the member 12, 25 and the passage extends at an inclination from the chamber 15, and is for the purpose of providing an air vent for the chamber.

In the modified form of the electrical coupling as shown in Figures 5 and 6, the reference character 30 indicates an electric wall outlet or socket member, and 31 indicates a plug for attachment to the outlet 30, as clearly shown in Figure 5.

Formed with the outlet or socket member 30 are inwardly extending diametrically oppositely disposed lugs 32 and 33 to be received in circumferentially and somewhat spirally extending bayonet slots 34 and 35 that are formed in the member or plug 31 and which are provided with mouth portions 36 and 37 that extend axially of 40 the plug 31 as clearly shown in Figure 6.

In the form as shown in Figures 5 and 6 I eliminate the latching means, but of course it will be apparent that the latching means such as indicated in the form as shown in Figures 1 to 45 4 could be used. However, when the lugs 32 and 33 reach the inner ends of the circumferentially arranged portions of the bayonet slots 34 and 35, the plug will be securely associated with the socket member, with the electric contact elements of the plug engaging the corresponding contact elements of the socket member as clearly shown in Figure 5.

From the above description and disclosure of the drawing, it will be obvious that I have pro- 55

vided a coupling that can be associated with different types of electrical devices for securing companion members thereof against casual displacement, and to assure a positive engagement of the contact elements thereof.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

- 15 1. An electrical coupling comprising a pair of companion members formed from insulating material and having centrally arranged longitudinally disposed bores therein with like arranged passageways extending from the outer ends of the bores, said passageways receiving conductors having enlarged terminals providing heads disposed in the bores and fitting and contacting the ends thereof to prevent withdrawal of the conductors from the members, one of said members being provided with bayonet slots and a groove, the latter extending longitudinally of its member, lugs formed with the other member and
- 20
- 25

receivable in the bayonet slots, latching means for said members and including a pawl carried by said other member, a head on one end of said pawl and being receivable in the groove for co-operation with the lugs and bayonet slots to hold the members together against circumferential and endwise displacement and with the bores in communication with each other to provide a chamber to receive a fuse, the latter having ends shaped to fit the heads for disposal in contact therewith.

2. An electrical coupling comprising a pair of companion members formed from insulating material and having centrally arranged longitudinally disposed bores having conical ends with 15 passageways extending therefrom and through the outer ends of said members, said passageways receiving conductors having enlarged terminals providing heads shaped to fit the conical ends and contacting the same to prevent withdrawal of the conductors through the passageways, means for detachably securing and latching the members together with the bores in communication with each other to provide a chamber adapted to receive a fuse with the ends of the latter in contact with the heads.

WILLIAM O. THOMAS.
